(57) **CLAIM**

The ornamental design for an article support stand, as shown and described.

DESCRIPTION

FIG. 1 is a perspective view of an article support stand showing my new design

FIG. 2 is a front elevation view thereof.

FIG. 3 is a rear elevation view thereof.

FIG. 4 is a right side elevation view thereof. A left side elevation view is a mirror image of the right side elevation view.

FIG. 5 is a top plan view thereof.

FIG. 6 is a bottom plan view thereof.

FIG. 7 is a cross-sectional view taken along the line 7-7 in FIG. 2.

FIG. 8 is an enlarged cross-sectional view taken along the line 8-8 in FIG. 2.

FIG. 9 is an enlarged cross-sectional view taken along the line 9-9 in FIG. 2, which omits the internal structure.

FIG. 10 is a perspective view of the article support stand in an alternate lower position.

FIG. 11 is a referential view showing use thereof; and, FIG. 12 is a referential view showing use thereof.

The broken lines shown in the drawings illustrate portions of the article support stand and environmental structure that form no part of the claimed design.

1 Claim, 12 Drawing Sheets
